UNITED STATES PATENT OFFICE.

HARRY F. WOERNLEY, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

DRAFT-GEAR ATTACHMENT.

1,136,079.

Specification of Letters Patent. Patented Apr. 20, 1915.

Application filed December 28, 1912. Serial No. 739,021.

To all whom it may concern:

Be it known that I, HARRY F. WOERNLEY, a citizen of the United States, residing at Pittsburgh, in the county of Allegheny and 5 State of Pennsylvania, have invented new and useful Improvements in Draft-Gear Attachments, of which the following is a specification.

This invention relates to railway draft 10 appliances, and more particularly to a swivel support for the draw-bar.

Where couplers of the rigid lock type are employed, it is necessary to provide means for permitting lateral as well as vertical movement of the draw-bar and according to one construction for this purpose, as shown in Patent No. 833,702 of C. H. Tomlinson, dated October 16, 1906, a swivel connection is provided at the rear 15 end of the draw-bar having a pivot pin arranged vertically for horizontal movement of the draw-bar and another pivot pin arranged horizontally to permit vertical movement of the draw-bar. With this prior 20 construction when a buffing stress is applied to the draw-bar there is a tendency to buckle or bend at the pivot pin for vertical movement, particularly in rounding curves, as this pin is between the other pivot pin 25 and the coupler head and therefore must transmit stresses through the pivot pin under compression.

The principal object of my invention is to 30 provide an improved draw-bar swivel in which the tendency to buckle is obviated.

In the accompanying drawing; Figure 1 is a top plan view of a draw-bar and coupler construction with my improvement applied thereto; Fig. 2 a side elevation thereof; and Fig. 3 a central horizontal section 35 of the improved swivel.

The invention is shown applied in the

drawing to a draw-bar and coupler construction comprising a rigid lock coupler 1 having a stem 2 within which is mounted a 45 draw-bar 3. The rear end of the draw-bar 3 is made in the form of a fork having jaws 4 between which is mounted a swivel connection 5. The swivel 5 is provided with a horizontal aperture 6 for pivot pin 7 and 50 forward of said aperture is a vertical aperture 8 for a pivot pin 9. A supporting member 10, secured to the car, is provided with bearings in which the pivot pin 9 is vertically mounted, a clearance space 11 being provided in said member, to permit the 55 swinging movement of the swivel 5.

It will now be evident that by arranging the pivot connection of the draw-bar 3 as shown, there is no joint in the line of compression when buffing stresses are applied, the compression being transmitted through the solid draw-bar to the pivot pin 7 and thence the stress is transmitted in tension 60 through the swivel 5 to the pivot pin 9 and 65 the car.

Having now described my invention, what I claim as new and desire to secure by Letters Patent, is:—

In a draft gear appliance, the combination 70 with a draw-bar, of a swivel connection mounted on a horizontal pivot pin carried by the end of the draw-bar, a supporting member secured to the car, and a vertical pin carried by said member and forming a 75 pivot for the swivel connection at a point intermediate the horizontal pivot pin and the outer end of the draw-bar.

In testimony whereof I have hereunto set my hand.

HARRY F. WOERNLEY.
